WATER CLOSET

Clarence E. Wexelberg, Detroit, and Theodore C. Hobbs, Birmingham, Mich., assignors to Briggs Manufacturing Company, Detroit, Mich., a corporation of Michigan

Application April 6, 1936, Serial No. 72,940

13 Claims. (Cl. 4—12)

This invention relates to water closets and particularly to water closets in which the bowl is enclosed or concealed.

An object of the invention is to provide improved means whereby conventional types of water closets having more or less unsightly bowl portions may be transformed into installations of pleasing and attractive appearance and wherein the transformation may be accomplished, if desired, without the necessity of any reconstruction or alteration of the standard closet bowl.

A further object of the invention is to provide a water closet with a bowl concealing panel or enclosing apron which can be applied to the previously installed water closet in an inexpensive and simple manner.

A further object of the invention is to provide a water closet of the foregoing character in which the bowl portion and also the flush tank are concealed from view by the application to the bowl and flush tank of pre-formed and shaped panels or enclosing housings.

The above and other objects and advantages of the invention will appear from the following description and appended claims when considered in connection with the accompanying drawing forming a part of this specification.

In said drawing:

Fig. 1 is a side elevation of a water closet and flush tank structure embodying the present invention.

Fig. 2 is a top plan view thereof.

Fig. 3 is a fragmentary vertical section, on an enlarged scale, taken substantially along the line 3—3 of Fig. 1; and

Fig. 4 is a detail fragmentary vertical section, on an enlarged scale, taken substantially along the line 4—4 of Fig. 1.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring now particularly to the drawing, there is shown a water closet having a bowl 10 provided with a base 10a. The bowl supports a conventional seat 12 provided on its under face with a rubber stop or bumper 13. The seat 12 in the

present instance is concealed by means of a lid 14 formed of sheet metal or the like and provided with rubber stops or bumpers 15 to prevent contact of the lid directly with the seat. The seat and cover, as shown, are mounted upon a pair of common hinges 16 supported in conventional manner by the bowl.

As seen in Figs. 1 and 3, the upper edge of the bowl 10 has an external surrounding bead or lip 11 provided with an undercut groove 11a (Fig. 10 3). As shown, the bead and groove extend around three sides of the bowl.

The water closet structure includes an upright flush tank 17 adapted to be enclosed at four sides preferably by means of a pre-formed cover or hood, shown as a whole at 18. The lower edges of the front and end or side walls of the hood may be provided with an internally disposed bead or beads 19 (Fig. 3) which are preferably formed by rolling the metal inwardly.

A panel or apron 20, formed of sheet metal or other similar material, is provided for concealing a plurality of sides of the bowl 10, such as the side walls and the front wall thereof. In the present instance it is generally U-shape in formation to enclose the three exposed sides of the bowl. The panel is preferably formed from a single sheet of material, such as metal, and stamped to provide an inwardly and upwardly extending flange 21 at its upper edge, an embossed strip or molding portion 22 adjacent its lower edge (Fig. 1) and a bead or rolled portion 23 at its lower edge (Fig. 4). The inner face of the panel 20, adjacent the bead or rolled edge 23 is provided with a plurality of metal clips or fastener members, shown as a whole at 25. The clip

comprises an outer leg 25a having a rolled or flanged lower edge providing a bead 26 and an inner leg 27 which, as shown, is straight and is spaced from the outer leg and connected thereto by a web or intervening strip of metal 25b. Each of the clips is substantially U-shaped in vertical cross section as shown in Fig. 4. The clip is preferably attached to the panel by spot welding although it may be secured thereto in any other suitable and convenient manner.

Before the panel 22 is applied to the closet bowl, an anchoring strip or member, such as the angle bar 30, is mounted upon the floor adjacent the base 10a of the bowl and extends around and in close proximity to three of its sides. This anchoring member 30, as shown, is U-shaped. In any event, its shape corresponds substantially to the outline or contour of the bowl base 10a. The anchoring member has a horizontal flange 31

and a vertical flange 32, the horizontal flange being attached to the floor in any suitable manner.

In applying the panel or shield to the water closet bowl, the hook members or clips 25 are slipped over the upright flange 32 of the anchoring member so that the legs 27 of the clips engage the inner face of said flange, as best seen in Fig. 4. The panel is then elevated to bring the top flange 21 thereof into position within the undercut groove 11a behind the bead or lip 11, as shown in Figs. 1 and 3. With the parts in this position a strip or mass of cement 33 is applied to the floor against the upright flange 32 in sufficient quantity to fill the space between the floor and the bottom or rolled edge or bead 23 of the panel. The cement serves to support the panel and maintain its flange 21 in engagement with the lip 11. If desired, and for ornamental purposes, a finish molding may be applied to the exterior of the panel to conceal the joint and cement. A suitable molding or finish strip for this purpose is shown at 35 and may be attached to the panel in any suitable manner, as by means of screws or the like 36.

25 The panel 20 and the finish molding 35 have an exterior finish corresponding to that of the bowl 10, the lid 14 and the tank hood 18. Thus the various parts of the whole structure have the appearance of being formed of the same material. 30 Inasmuch as the flange 21 fits neatly beneath and is concealed by the lip 11 around all of the exposed sides of the bowl, the ornamental appearance of the article is enhanced.

As mentioned above and as shown in Fig. 1, 35 the flush tank 17 is preferably enclosed or housed by means of a metallic pre-formed enclosing casting or hood 18. The bottom edges of the front wall and the end walls of the hood 18 are preferably rolled or coiled to form a bead or beads 19, 40 Fig. 3. Thus the danger of injuring the hands when removing the hood is eliminated by the absence of any sharp edges. The exterior surfaces of the hood 18 are provided with a finish, such as vitreous enamel, corresponding to that 45 of the other parts of the closet structure. The hood 18 may be formed by a stamping operation from a single blank of sheet metal.

While I have illustrated the use of my invention in connection with a vitreous bowl, it will 50 be understood that it may be employed in connection with bowls of various types and shapes. Moreover, while I have shown one form of means for attaching the panel or apron to the bowl it will be understood that various other means for this purpose may be employed. The panel may be supported by means of a layer or body of cement without the use of the molding or finishing strip 35. It is also possible to support the panel 20 in various other ways and without the 55 use of cement, such, for example, as by employing a finish molding or strip, such as the strip 35, and applying the strip to the lower edge of the panel by the use of screws such as the screws 36, which are alined or brought into register with 60 and threaded into preformed apertures or openings formed in the panel. Furthermore, the anchoring device 30 may be attached to the base of the bowl or mounted upon the floor, as illustrated herein.

70 We claim:

1. A water closet having a bowl, and a pressed metal panel enclosing a plurality of sides of said bowl and extending from the bowl to a substantially horizontal supporting surface around the front and a side or sides of the bowl.

2. A water closet having a bowl, a flush tank associated with said bowl, a pressed metal panel removably mounted upon said tank for enclosing a plurality of sides thereof, and a pressed metal panel having substantially vertical walls enclosing a plurality of sides of said bowl and spaced therefrom through the major part of the height thereof. 5

3. A water closet having a bowl mounted upon a floor surface, a removable panel for enclosing and concealing a plurality of sides of said bowl, and means on said floor surface cooperating with the lower edge of said panel for maintaining the panel in enclosing position about the bowl in spaced relation to the bottom of the bowl. 10 15

4. A water closet structure including a bowl having an undercut bead at its upper edge, a substantially U-shaped member located at the base of the bowl and surrounding a plurality of sides thereof, a substantially U-shaped panel enclosing 20 a plurality of sides of said bowl and said member, said panel having its upper edge engageable with said undercut bead, and a clip carried by said panel adjacent the bottom edge thereof engageable with said U-shaped member. 25

5. A water closet structure including a bowl having an external bead at its upper edge, a substantially U-shaped member located at the base of the bowl and surrounding three sides thereof, 30 a panel enclosing three sides of said bowl and said member, said panel having its upper edge engageable with said bead, and a plurality of devices attached to the inner face of said panel adjacent its lower edge for detachable engagement with said U-shaped member to hold the 35 panel in enclosing position about said bowl.

6. A water closet structure including a bowl having an undercut bead at its upper edge, a substantially U-shaped member located at the base of the bowl and surrounding a plurality of sides 40 thereof, a panel enclosing a plurality of sides of said bowl and said member, said panel having its upper edge engageable with said undercut bead, a plurality of devices attached to the inner face of said panel adjacent its lower edge for detachable engagement with said U-shaped member to hold the 45 panel in enclosing position about said bowl, and a molding strip surrounding the base of said panel.

7. A water closet including a bowl adapted to 50 be mounted upon a floor surface and formed of vitreous material or the like having an external undercut bead at its upper edge, an anchoring member located on said floor adjacent the base of said bowl, and a panel surrounding a plurality 55 of sides of the bowl and having means at its upper and lower edges engaging respectively said bead and said anchoring member.

8. A water closet including a bowl adapted to be mounted upon a floor surface and being 60 formed of vitreous material or the like having an external depending flange extending around three sides thereof at its upper edge, an anchoring member located on the floor adjacent and extending around three sides of the base of said 65 bowl, a panel enclosing three sides of the bowl and having a surrounding flange at its upper edge engaging beneath said bowl flange, and a plurality of clips carried by the inner face of said panel adjacent its lower edge for releasably engaging said anchoring member to maintain the panel in enclosing position about said bowl. 70

9. A water closet including a bowl having a rim and a base adapted to be set upon a floor surface, said bowl being formed of vitreous material, 75

an anchoring member located adjacent and extending around three sides of the base of said bowl, a panel enclosing three sides of the bowl and having a surrounding flange at its upper edge engaging said bowl rim, means for attaching the lower edge of the panel to said anchoring member, and a molding strip attached to the outer face of said panel at the base thereof.

10. A water closet comprising a bowl and a base therefor adapted to be mounted upon a floor surface, and a pressed metal panel enclosing a plurality of sides of said bowl and base and extending substantially vertically from the rim of said bowl to said floor surface at points spaced 15 outwardly from said base.

11. A water closet comprising a bowl provided with a rim and a base adapted to be mounted upon a floor surface, an anchoring member extending around a plurality of sides of the base 20 and spaced outwardly therefrom, and a pressed metal panel enclosing a plurality of sides of said bowl and base and extending substantially vertically from said rim to the anchoring member and attached to said member.

25 12. A water closet having a bowl provided with

a rim and a base adapted to be mounted upon a floor surface, anchoring members located on said floor at three sides of said base and spaced outwardly therefrom, and a panel formed from a metal stamping adapted to enclose three sides of 5 said bowl and said base, the upper edge of said panel engaging said bowl rim and the lower edge of the panel engaging said anchoring members.

13. A water closet having a bowl provided with 10 a rim and a base adapted to be mounted upon a floor surface, anchoring members located on said floor at three sides of said base and spaced outwardly therefrom, a panel formed from a metal stamping adapted to enclose three sides of 15 said bowl and said base, the upper edge of said panel engaging said bowl rim and the lower edge of the panel engaging said anchoring members, and a molding strip corresponding in contour to the contour of said panel and adapted to be attached 20 to the base of the panel to conceal the same and said anchoring members.
